UNITED STATES PATENT OFFICE.

HENRY VINCENT SMITH, OF SOUTH YARRA, NEAR MELBOURNE, VICTORIA.

MAGNETIC LOCK.

SPECIFICATION forming part of Letters Patent No. 478,245, dated July 5, 1892.

Application filed December 18, 1891. Serial No. 415,480. (No model.)

To all whom it may concern:

Be it known that I, HENRY VINCENT SMITH, gentleman, a subject of the Queen of Great Britain, residing at No. 33 Cunningham Street, 5 South Yarra, near Melbourne, in the British Colony of Victoria, have invented a Magnetic Lock, principally applicable to doors, gates, boxes, and drawers, of which the following is a specification.

10 This invention consists of a magnetic lock, principally applicable to doors, gates, boxes, and drawers, and which will automatically lock itself when such doors, &c., are closed; and it consists in certain parts and combinations thereof hereinafter more fully described and claimed.

Referring to the accompanying drawings, Figure 1 is a front elevation of a door, shown partly in section in order to illustrate one 20 form of my magnetic lock, in which the magnet is fixed within the door and the catch within the door-jamb. Fig. 2 is a section through said lock, showing the catch in its unlocked position—that is to say, as it would be before the door is closed. Fig. 3 is a similar view to Fig. 2, but showing said catch in its locked or engaged position—that is to say, as it would be after the door is closed. Fig. 4 is a detached side elevation of a modified 25 form of said catch. Fig. 5 is a sectional view showing a modification of my magnetic lock. Fig. 6 is a similar view to Fig. 1, but illustrating the catch as being pivotally supported at its lower end, instead of depending from a pivot at its upper end. Fig. 7 shows another 30 modification of my magnetic lock, which is specially adapted for a drawer. Fig. 8 is a sectional view of another modification illustrating the employment of a sliding catch or bolt.

The same letters of reference indicate the same or corresponding parts in all the figures.

Referring first to Figs. 1 to 3, A represents the permanent magnet, which is inserted 45 within the door opposite to the pivoted or depending catch or tumbler B. This latter is preferably constructed of iron, though, if preferred, it can be made of some other material, so long as it has a strip or piece of iron 50 cured upon the side adjacent to the magnet A, as will be well understood. In either case when the door is closed the catch will be

drawn by the magnet A into the recess C, as shown in Fig. 3, said recess being formed for the purpose in the door, the result being of course to effectually lock said door. The catch B is formed with a projecting arm or finger D, which is bent at right angles near its end and so constructed and arranged that it can be pushed back with the aid of a key, 60 (indicated by dotted lines at E,) so as to withdraw or force the catch B from engagement with the recess C, overcoming the resistance of the magnet A, and thus releasing the door.

In order to prevent a knife from being slid 65 down between the catch B and the magnet A, so as to push back said catch without using the key, I form the said catch with a notch or projection F on its forward edge, so that when said catch is in its projected or locked position said notch or projection will extend across the space between the door and its jamb, as illustrated in Fig. 3, thus forming an effectual stop to the downward passage of a knife or similar implement. 70

The catch or tumbler B must be pivotally supported in such a manner as to give it a tendency to remain in the position shown in Figs. 1 and 2, although, if preferred, a spiral or other spring may be employed for returning said catch or tumbler into this position. Instead of the finger D, the catch B may be provided with an oval-shaped hole or recess D, as illustrated in Fig. 4, the key E being inserted within said hole or recess 80 and turned round into the position indicated in dotted lines in said figure, in order to unlock or withdraw the catch B. This latter may be formed with a projecting portion b, as shown in Fig. 4, instead of its front edge 85 being straight, and, if preferred, it can be pivoted at its lower end, as illustrated in Fig. 6, instead of depending from its upper end. This projection b is only for the purpose of giving a greater hold or bite to the catch. 90

If preferred, the catch B can be made with a projecting loop D, as illustrated in Fig. 5, and a spindle e, having a projecting cross-piece or double arm E, may be passed through either the door or door-jamb, as the case 100 may be, said cross-piece or double arm being arranged to bear against the back of the loop D to enable the catch B to be withdrawn by turning said spindle e in either direction. 95

A knob or handle is provided on one or both of the ends of said spindle to enable it to be turned in either direction when it is required to open the door. The spring *e*' serves to 5 turn the spindle *e* to its normal position.

In order that the catch *B* may be locked in its projected or engaged position, I mount a cam *G* behind the loop *D* and form a sided recess *g* in said cam at about the place where 10 said cam is centered or supported, said recess being adapted to receive the correspondingly-sided end of a key, whereby said cam can either be turned back into its withdrawn position, as shown in Fig. 5, or can be turned 15 round, so that it bears against the back of the loop *D*, and thus holds the catch *B* in its projected position. With this arrangement the door will be latched automatically as soon as it is closed, and can then be opened only by 20 turning the spindle *e*, while if the cam *G* is turned into its locking position the door can only be unfastened by first inserting a key into the recess *g* in the cam *G* and turning said cam back into the position shown in Fig. 5.

When my magnetic lock is to be applied to a drawer or other similar article of furniture, I prefer to pivot the catch *B* at about its center, as illustrated in Fig. 7, and to arrange the magnet *A* so that when the drawer is closed 25 it will draw down the end of said catch into engagement with the recess *C*, the opposite end of the catch *B* being of course made sufficiently heavy to normally hold said catch in its horizontal position. A key *E* is provided 30 to enable the free end of the catch *B* to be pushed down in order to raise the opposite end out of engagement with the recess *C* whenever it is required to open the drawer.

In lieu of using pivoted catches, as above

described, they can be arranged to slide into 40 or out of engagement with the recesses *C*, in which case I use spiral or other springs—such as *b*—to return said catches to their unlocked positions, the magnet *A* in this case of course being strong enough to overcome the 45 resistance of the spring *b*.

Having now particularly described and ascertained the nature of my said invention and in what manner the same is to be performed, I declare that what I claim is—

1. In a magnetic lock, the combination, with 50 the permanent magnet, of the pivoted latch and means on said latch whereby it may be actuated by a key, substantially as set forth.

2. In a magnetic lock, the combination of 55 a permanent magnet, the pivoted latch adapted to be drawn into recess by action of said magnet, and means on said catch whereby the same may be disengaged from said magnet and recess, substantially as set forth.

3. In a magnetic lock, the combination of 60 the latch and a notch in the upper end of said latch, adapted to prevent the insertion of a knife or analogous device between the latch and magnet to disengage the said latch from the magnet, substantially as set forth.

4. In a magnetic lock, the combination, with 65 the permanent magnet, of the pivoted latch having a loop, means operating within said loop to move the pivoted latch away from the magnet, and a cam adapted to be operated by a key to secure the latch in a locked position, substantially as set forth.

HENRY VINCENT SMITH.
